UNITED STATES PATENT OFFICE.

JOHN W. McCULLOCH, OF HASKELL, NEW JERSEY.

INDICATING DEVICE.

1,194,522

Specification of Letters Patent. Patented Aug. 15, 1916.

Application filed October 6, 1915. Serial No. 54,389.

To all whom it may concern:

Be it known that I, JOHN W. McCULLOCH, a subject of the King of England, residing at Haskell, in the county of Passaic and State of New Jersey, have invented certain new and useful Improvements in Indicating Devices, of which the following is a specification, reference being had to the accompanying drawings.

10 This invention relates to certain improvements in indicating devices and has relation more particularly to a device of this general character especially designed and adapted for use in connection with vehicles; 15 and it is an object of the invention to provide a novel and improved device of this general character whereby a signal may be given to indicate to a following vehicle the direction in which a turn is to be made. 20 Furthermore, it is an object of the invention to provide novel and improved means whereby illuminating means for the signal is under control of said signal.

The invention consists in the details of 25 construction and in the combination and arrangement of the several parts of my improved indicating device whereby certain important advantages are attained and the device is rendered simpler, less expensive 30 and otherwise more convenient and advantageous for use, all as will be hereinafter more fully set forth.

The novel features of the invention will be carefully defined in the appended claim.

35 In order that my invention may be the better understood, I will now proceed to describe the same with reference to the accompanying drawings, wherein—

Figure 1 is a diagrammatic view in perspective illustrating an embodiment of my invention, the coacting portion of the vehicle being indicated by dotted lines; Fig. 2 is an enlarged fragmentary view in elevation illustrating the operating levers carried by the steering column; Fig. 3 is a view in top plan of the device as disclosed in Fig. 1, the steering column being shown solid for convenience of illustration; and Fig. 4 is a view, partly in section and partly in perspective, illustrating the indicating member as herein set forth.

It is to be understood in practice that it is my purpose to have an indicator disposed at the rear of the vehicle at opposite sides 55 thereof but as each of said indicators and its coacting parts are substantially dupli-

cate, it is thought that a description of one will suffice for the purpose of disclosure.

As disclosed in the accompanying drawings, 1 denotes a vertically disposed casing having 60 its outer side face open and being suitably supported upon a rear mud guard or fender 2. Pivotedly mounted within the casing 1 is 65 the signal or indicator 3, herein disclosed as in simulation of a hand, and said signal, 70 when in lowered position, is entirely housed within the casing 1 but when elevated projects beyond the casing and indicates to a following vehicle the direction in which a 75 turn is to be made.

The signal 3 is provided with a tail 4 to which is engaged the flexible member 5, preferably wire, which is disposed through the tubing 6, said tubing being arranged along and beneath the fender 2 and forwardly 80 of the vehicle and disposed upwardly of the steering column 7 and terminating in close proximity to the rock lever 8 movable in a direction preferably transversely of the vehicle. The flexible member or wire 5 is secured to said lever intermediate the length 85 thereof whereby it will be perceived that as said lever is moved inwardly the signal 3 will be elevated. The projected portion of the signal possesses sufficient weight as to fall by gravity within the casing 1 when the lever 8 is released.

The lever 8 is disposed through a slot 9 arranged in the bracket 10 secured to the steering column 7, the inner end of the slot 90 9 being offset, as at 11, to receive the lever 8 in order to maintain the signal 3 elevated. It is also to be observed that the outer end of the bracket 10 is provided with the pulley 12 over which the flexible member or wire 95 5 is disposed in order to assure the requisite elevation of the signal 3. Carried by the top of the casing is a bracket 14 adapted to overlie the signal 3 when elevated and the outer extremity of the bracket is provided 100 with the lamp 15 of a conventional electrical type and in electrical connection with a suitable source of power B carried by the vehicle proper. Interposed in said circuit, preferably on the dash of the vehicle, is a 105 main switch S whereby said circuit may be opened or closed manually, and also interposed in said circuit are the contact members 16 and 17, the contact 16 being carried by the casing 1 and the second contact being 110 carried by the signal 3. By this arrangement, it will be seen that with the main

115

switch closed, the light or lamp 15 will be automatically caused to illuminate when the signal 3 is elevated.

In practice, I find it desirable to have the 5 tubing 6 filled with grease or other lubricant in order to facilitate the movement of the flexible member and to prolong the life thereof.

From the foregoing description, it is 10 thought to be obvious that an indicating device constructed in accordance with my invention is of an extremely simple and comparatively inexpensive nature and is particularly well adapted for use by reason of 15 the convenience and facility with which it may be assembled.

I claim:

In combination with a vehicle, a casing carried by the rear thereof, an indicator piv-

otally supported by the casing, means for 20 elevating the indicator, a bracket carried by the casing, a lamp carried by the bracket in electrical connection with a source of supply, said connection having interposed therein a contact carried by the indicator, and a 25 contact carried by the bracket, the contact carried by the indicator engaging the second contact when the indicator is elevated, the engagement of the contact serving to limit the upward movement of the indicator. 30

In testimony whereof I hereunto affix my signature in the presence of two witnesses.

JOHN W. McCULLOCH.

Witnesses:

JOHN W. WHETHAM,
EUGENE MATTHEWS.
